CANDLESTICK

James E. Vickers, 3005 Garfield St.,
Tallahassee, Fla. 32301

Filed Nov. 12, 1975, Ser. No. 631,311

Term of patent 14 years

Int. Cl. D26—01

U.S. Cl. D48—2

Fig. 1

Fig. 2

Fig. 3

Fig. 4

FIG. 1 is a side elevational view of a candlestick showing my new design with the candle shown in broken lines for illustrative purposes only,

FIG. 2 is a perspective view on an enlarged scale thereof;

FIGS. 3 and 4 are respectively top and bottom plan views thereof.

I claim:

The ornamental design for a candlestick, as shown and described.
